UNITED STATES PATENT OFFICE.

WILLIAM LOUDEN, OF FAIRFIELD, IOWA.

HOLDER FOR CATTLE-STANCHIONS.

1,097,809.

Specification of Letters Patent.

Patented May 26, 1914.

Application filed November 22, 1909. Serial No. 529,211.

To all whom it may concern:

Be it known that I, WILLIAM LOUDEN, residing at Fairfield, in the county of Jefferson and State of Iowa, have invented a new and useful Improvement in Holders for Cattle-Stanchions, of which the following is a specification.

My invention relates to holders for supporting cattle stanchions, and it consists of an improvement whereby the stanchion may be readily adjusted backward and forward to suit the length of the cow to be held thereby, and in other respects as set forth in the specification, and more specifically 15 pointed out in the claims.

In the accompanying drawings forming part of the specification, Figure 1 is a perspective of a portion of a series of stalls fitted with stanchions, and holders embodying the features of my invention. Fig. 2 is a transverse section on line 2—2 of Fig. 1, looking in the direction of the arrow. Fig. 3 is the same enlarged on line 3—3 of Fig. 1. Fig. 4 is an enlarged top view of one 25 of the upper holders showing a portion of the top-rail of the stall. Fig. 5 is a transverse section on line 5—5 of Fig. 3. Fig. 6 is an enlarged side view of one of the lower 30 holders, showing a section of the floor to which it is attached. Fig. 7 is an enlarged top view of the plate of the lower holder showing the upper ends of the bolts which hold it in place.

Referring to the drawings, A represents 35 the top-rail of a series of stalls and B the posts for the same set on a floor W and secured to the top-rail by clamps C. The stalls are provided with stanchions S which are fitted at their upper ends with connecting means, preferably chains D, which are connected to holders E on the top rail A, and at their lower ends with chains F which are connected to holders G, attached to the floor. The top rail, by means of the holders 40 E, constitutes an overhead support for the stanchions S.

The upper holders E which are attached at one end to the top-rail A, are composed of two clamping members H and I which are 45 held in contact with the rail A by bolts J, and attached to them is a toothed section K, as most plainly shown in Figs. 3, 4 and 5. The upper member H has an extended end which is provided with vertically set lugs h spaced apart and fitted with holes for a bolt L. Inside of the lugs h the body of the ex-

tended end is preferably made concave on its under side as shown in Fig. 5. The lower member I is provided with an extended end which fits in and bears against the concave portion of the member H and thus helps to support it in position. It is also provided with lugs i spaced apart and fitted with holes for a bolt N. The ends of the toothed section K are preferably bent inwardly so as to stand approximately in line with its toothed ends O, and are fitted with holes to receive the bolts L and N when inserted between the lugs h and i, so that the toothed section K will be securely held in place by 70 the members H and I which in turn are held securely in contact with the top-rail A by the bolts J.

By placing a link of the chain D in either of the spaces between the ends O of the toothed section which is transversely set, the stanchion will be held in either of the positions occupied by said spaces, and by this means it will be adjusted closer to or farther from the line of the rail A and post B to 80 the extent of the distance between the end spaces of the toothed section K. The members H and I may also be set on the rail so that the toothed section will extend on either side, as shown in Fig. 1, and this will 85 practically double the amount of the adjustment which may be made.

At the lower end of the stanchion a plate P is used to which a toothed section Q (preferably an exact duplicate of the section K) is attached. The plate is provided with a raised portion running centrally and longitudinally on its upper side, and terminating at each end with raised lugs R spaced apart with openings between them and fitted with holes for bolts T. The holes in the lugs R and in the ends of the toothed section Q are made to co-incide so that when the ends of the former are inserted in the space between the latter the bolts T will 100 pass through the co-inciding holes and the section Q will be attached to the plate thereby. The plate P which is also transversely set is fitted with a series of holes U to receive bolts V by means of which the plate 105 is attached to the floor W. The lower stanchion chain F, is connected to the section Q, the same as the upper chain D is secured to the section K and may be adjusted thereon in the same way. The plate P may 110 also be adjusted back and forth on the floor by passing the bolts V through either of the

series of holes U so that the section Q may be set centrally in line with the top-rail and posts of the stalls, or be set to either side, thus practically doubling the adjustment 5 which may be made of the section Q alone, and setting the stanchion forward or back as may be required.

The extended end of the member I is preferably made concave on its upper side 10 (as shown in Fig. 5) so as to lighten it. Its lower side is made so as to come in contact with the teeth O of the section K, thus closing the spaces between them and preventing the chain from slipping from one 15 to the other, thus forming separated attaching points for the links of the stanchions. The raised portion on the plate P is also constructed to come in contact with the teeth of the section Q for the same purpose. Instead 20 of the bolts L, N and T, rivets may be used to connect one end of the sections K and Q to the members H and I and the plate P, but the other end should be connected by bolts or keys which may be removed 25 so the sections may be opened to change the adjustment of the stanchion.

The invention is simple and inexpensive as well as neat and sanitary. The adjustments are readily made and when made the 30 stanchion is securely held in position. When wooden stalls are used, the plate P may be used to make the attachment to the under side of the top-rail of the stall in place of the members H and I which are 35 adapted for attachment to pipes or round bars. The members H and I may however be modified to fit hexagon bars or rails of other shapes. Instead of the chains D and F, other suitable means of attachment may 40 be substituted, and other means may be substituted for the sections K and Q, without departing from the spirit of my invention, the essential thing being the horizontally disposed member or members embracing 45 and rigidly secured at one end to the top rail and extended at substantially right angles to one side thereof, and adapted to support a stanchion at different points on said extended end.

50 What I claim is:—
1. In holders for cattle stanchions, the

combination with a top supporting rail, of a stanchion fitted at its upper end with connecting means, a horizontally disposed member embracing and rigidly attached at 55 one end to said top rail and extending at substantially right angles to one side thereof, and means for attaching and holding the stanchion at definite points along the extended part of the member. 60

2. The combination with a top supporting rail, of a stanchion fitted at its upper end with connecting means, a horizontally disposed member consisting of two parts embracing and rigidly clamped at one end to 65 said top rail and extending at substantially right angles to one side thereof, and a toothed section connected to said member for attaching and holding the stanchion at definite points along the extended part of 70 the member.

3. The combination with a stanchion fitted with connecting means at its upper end, of a top rail, upper and lower members secured to said top-rail and having ends 75 extended to one side thereof, the extended end of the lower member being adapted to support the extended end of the upper member, supporting lugs on the body of the lower member and on the extended end of 80 the upper member, a toothed section affixed to said lugs, and the connecting means of the stanchion attached to the toothed section so that it may be adjustable thereon.

4. The combination with a stanchion fitted with connecting means at its upper end, of a top rail, upper and lower members secured to said top-rail and having ends extended to one side thereof, the extended end of the upper member being concave on its under side and the extended end of the lower member fitted into said concave portion so as to support the extended end thereof, a toothed section affixed to the members, and the connecting means of the 95 stanchion attached to the toothed section so that it may be adjustable thereon.

Fairfield, Iowa, November 19, 1909.

WILLIAM LOUDEN.
